UNITED STATES PATENT OFFICE.

HAROLD K. PARSONS, OF SOUTHBRIIDGE, MASSACHUSETTS.

OPHTHALMIC MOUNTING.

Application filed June 15, 1920. Serial No. 389,073.

To all whom it may concern:

Be it known that I, HAROLD K. PARSONS, a citizen of the United States, residing at Southbridge, in the county of Worcester and State of Massachusetts, have invented certain new and useful Improvements in Ophthalmic Mountings, of which the following is a specification.

This invention relates to improvements in ophthalmic mountings and has particular reference to that type of mounting intended to be retained on the face through spring actuated guard levers.

One of the principal objects of the present invention is to provide a novel and improved type of bearing and manner of attaching the actuating levers to insure ready assembling of the parts, reduction of wear to a minimum, and thus proper holding and alignment of the several parts of the mounting and of the mounting itself on the face when in use.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a front view of a mounting embodying my improvements.

Figure II represents a fragmentary sectional view of one form thereof.

Figure III represents a similar view of another form.

Figure IV represents a similar view of an enclosed type.

In the drawings, the numeral 1 designates the bridge or lens connecting member provided at each end with the clips 2 adapted to receive and retain in position the lenses 3. One of the great advantages of the type of mounting here illustrated resides in the fact that the lenses are connected by a rigid bridge 1 and hence under ordinary conditions will be positively maintained in correct

relationship one to the other. One of the difficulties experienced with this type of mounting in the past has been due to the fact that the bearings have been insufficient, with the result that the levers have tended

to loosen and wobble and thus the mounting as an entirety has not been properly retained on the face. 55

A further difficulty has been hitherto experienced in connection with these mountings due to the fact that the parts have been 60 so related as to be difficult of assembling in the original manufacture or difficult of replacement should any become worn or broken.

It is, therefore, the purpose of my invention to provide a mounting so far as possible modifying the defects of prior art constructions. 65

In carrying out this principle in the form of my invention illustrated in Figure II, I 70 have formed at each end of the bridge 1 the flattened portions 4 having the central apertures 5 formed therethrough surrounded by the upstanding flange or wall 6 preferably in the form of a tube. Disposed beneath 75 the portion 4 of the bridge and serving as a support therefor is the guard lever 7 having the actuating handle 8 and nose engaging portion 9, the said lever thus serving as a support for the bridge with a wide flat 80 portion bearing thereagainst to insure maximum contact surface, tending to eliminate possible wabbling of the parts, it being understood that the guards are clamped against the nose as through the action of the springs 85 10 and serve as substantially stationary parts retaining the remainder of the mounting in position.

To pivotally connect the guard member 7 with the mounting I preferably form it 90 with an upstanding pivot portion 11 which fits within the aperture 5 and inside the tubular sleeve 6 which provides a long vertical bearing for the pivot on the lever cooperating with the bearing of the under 95 side of the bridge against the top of the lever to most steadily and satisfactorily retain the parts against relative tilting or wabbling movement and the long bearing thus provided insuring maximum durability of 100 the parts under the wear of ordinary service conditions.

It is to be noted that in this form the spring 10 is shown as surrounding the tube 6, one end preferably bearing against the 105 lens attachment 2 and the other end being suitably connected with the guard lever to inwardly actuate the same. While the

2
weight and bearing of the parts when in use will retain the bridge and guard lever in position to lock the same against separation, I make use of a cap member such as the 5 screw head 12 having the screw 13 engaging the upper portion of the pivot member 11 locking it in position. It is to be noted that this cap member is of sufficient size to in addition overlie the spring 10 and retain it 10 in place on the tube 6. It will thus be seen that I have provided an extremely satisfactory and easily assembled construction, in that the lever may be slipped into place from the under side of the bridge with its 15 rigid pivot extending up through the bridge, while the spring may be separately applied or removed over the member 6 and the single cap member serves to satisfactorily lock both parts together.

20 Figure III illustrates a slight variation in the construction, in which in place of making the pivot member 11 as a solid tapped out stud, such as indicated in Figure II, the member 11 is in the form of a tube 25 having the upper portion smooth and the lower portion threaded to engage the lower threaded end of the screw 13 so that the screw may be dropped into the upper portion of the tube and then tightened in the 30 lower portion to securely lock the parts together, the height of the pivot 11 being preferably slightly greater than the combined thickness of the bridge and member 6 so that the screw may be securely tightened without binding against any portion of the lens supports.

Figure IV illustrates a slight modification of the construction in which in place of the second tube 6 being employed integral with 40 the bridge, the actuating spring 10 is slipped directly over the upwardly projecting portion of the pivot member 11, while a cup sleeve or tube 14 encircles the spring 10 and has an end portion 15 interlocking with the 45 upper end of the pivot 11, a tongue 16 on

the pivot holding the cap for rotation therewith while the screw 13 serves to connect the parts. In this form it will be seen that the cap member overhangs and comes down against the bridge 1 and provides a bearing 50 preventing longitudinal play of the pivot member 11 through the bridge and helps when needed to form a supplemental bearing to steady the lever and prevent any wobbly movement thereof during its pivot- 55 ance even as it and the bridge may wear.

I claim:

1. In a device of the character described, the combination with a bridge member having a pivot receiving aperture therethrough, 60 of a guard lever having an upstanding pivot portion extending through the aperture in the bridge portion, an actuating spring for the lever resting on the bridge and surrounding the pivot projection of the lever and a 65 cap member carried by the pivot projection of the lever overlying the spring and slidably engaging a portion of the bridge for retaining the several parts in position.

2. In a device of the character described, 70 the combination with a bridge member having a pivot receiving aperture therethrough, of a guard lever having an upstanding tubular pivot portion extending through the aperture in the bridge portion, an actuating 75 spring for the lever resting on the bridge and surrounding the pivot projection of the lever, a cap member carried by the pivot projection of the lever overlying the spring and slidably engaging a portion of the 80 bridge for retaining the several parts in position, and means securing the cap against independent rotation with respect to the lever.

In testimony whereof I have affixed my 85 signature, in presence of two witnesses.

HAROLD K. PARSONS.

Witnesses:

ALICE G. HASKELL,
ESTHER M. LOFLER.
